UNITED STATES PATENT OFFICE.

CHARLES J. MILLER, OF MINNEAPOLIS, MINNESOTA, ASSIGNEE, BY MESNE ASSIGNMENTS, TO THE LAMSON COMPANY, OF BOSTON, MASSACHUSETTS, A CORPORATION OF NEW JERSEY.

STORE-SERVICE APPARATUS.

1,085,752.

Specification of Letters Patent.

Patented Feb. 3, 1914.

Application filed April 29, 1911, Serial No. 624,183. Renewed May 1, 1913. Serial No. 764,935.

To all whom it may concern:

Be it known that I, CHARLES J. MILLER, of Minneapolis, Hennepin county, Minnesota, have invented certain new and useful Improvements in Store-Service Apparatus, of which the following is a specification.

My invention relates to an improved construction for the home station and the object of the invention is to simplify and improve the means for propelling the carrier from the station and also to provide means for checking the carrier as it enters the station by means of a cushion mechanism which will prevent damage to the carrier and its connections.

A further object is to provide improved means for mounting the line wire in the station and improved supports for the cord by which the basket is raised and lowered.

20 A further object is to provide means to positively prevent the propulsion of the carrier from the home station until the basket is attached to the carrier.

Other objects of the invention will appear 25 from the following detailed description.

The invention consists generally in various constructions and combinations, all as hereinafter described and particularly pointed out in the claims.

30 In the accompanying drawings forming part of this specification, Figure 1 is a side view of a store service apparatus embodying my invention, Fig. 2 is a detail sectional view, Fig. 3 is a plan view, the supporting 35 hanger being shown in section.

In the drawing, 2 represents a hanger secured to the ceiling and 3 are parallel barrels or cylinders connected by a web 4 which is provided with an upright, centrally arranged hub 5 that is adapted to receive the lower end of the hanger and is secured thereto by a set screw 6. A web 7 also connects the barrels 3 and to this web the line wire 8 is secured, preferably midway between the barrels 40 and beneath the same. As shown in Fig. 2, I prefer to employ a tapered pin 8' for securing the end of the line wire in its support. The barrels are open at each end and brackets 9 and 10 have studs 45 slidable in the open ends of said barrels and capable of rotation therein and are secured by set screws 11. These brackets carry pulleys 12 and 13. A cord 14 passes over the pulleys 12 and 13 and is attached to a basket raising

hook 15 by means of which the basket 16 is 55 raised into engagement with the carrier 17 preparatory to sending the basket from one station to another or lowering it to a position where the basket may be reached by the clerk. The adjustment of the bracket 9 allows the distance between the pulleys to be increased or decreased and the basket centered beneath the carrier. The rod 18 is attached at its forward end to the web 7 and extends backwardly therefrom and is supported at its rear end by a guy wire 19. A plunger 20 has guides 21 at its forward and rear ends, the forward guide being slidable on the line wire 8 and the rear guide on the rod 18, and said plunger has a yielding 70 buffer 21' at its forward end in position to engage a latch yoke 22 that is pivoted at 23 on the carrier 17. This latch is in the form of a yoke and has a rearwardly extending part which engages a hook 22' mounted on a stud 23' that is slidable in the web 7 and is yieldingly held against movement in either direction by springs 24 and 25. A spring 26 mounted on the carrier normally holds the latch yoke in position to engage 75 the hook 22'. The carrier is provided with a yielding buffer 27 which engages the end of the hook 22', and the pin 28 limits the upward swinging movement of the latch yoke 21.

One end of a propelling cord 28' is attached to the rear end of the plunger and extends forward over a pulley 29 and from thence downward over a pulley 30 mounted in a bracket 31 carried by arms 32 and below said pulley the cord is provided with a pulley 33 having a frame provided with a tube extension 34 which surrounds the cord and prevents the pulley from turning over when the cord is returned to starting position. A hand grip 35 is mounted on a cord 35' below the pulley 33 within reach of the clerk. A roller 36 is preferably provided between the arms 32 to serve as a buffer for the basket and load as it arrives at the station, thus stopping it properly and preventing strain on the car and wire. The upper ends of the arms 32 are pivotally connected with pins 37 which have springs 38 mounted thereon and are slidable in ears 39 provided on the barrels 3. The arms 32 are pivoted at 32' on the web 7 and are adapted to oscillate on said pivots, and arms 40 have a com-

mon pivot with the arms 32 and project forwardly therefrom on each side of the path of the carrier in the path of the ascending basket, to be engaged thereby and yieldingly 5 resist its upward movement. Springs 41 mounted on bolts 42 serve as cushions to resist upward movement of the arms 40, and to throw back the basket elevator hooks after the basket is latched to the car, so car 10 can depart from the station. The cord 14 is also provided with a hand grip 43 for use in raising or lowering the basket. One end of the cord is utilized for handling the basket while the other end operates to propel 15 the plunger and drive the carrier from the station.

The barrels 3 may be swung around in a horizontal plane to allow the line wire to be attached at any point around the circumference of the hanger and the forward movement of the plunger operating to simultaneously disengage the latch yoke from the hook 22 and force the carrier out of the station with the continued movement of the 25 plunger.

As shown in Fig. 2, I prefer to provide a tilting lever device 17' pivoted at a point intermediate to its ends in the carrier 17 and normally adapted to swing into the path 30 of the latch 22 and prevent it from being tripped by the movement of the plunger to project the carrier from the station before the basket has been hung thereon. Obviously, an inexperienced clerk or one in the 35 hurry of waiting on a customer might pull the wrong cord and instead of raising the basket to the carrier might actuate the plunger to drive the carrier from the station. This would result in considerable annoyance 40 and waste of time in getting the carrier back to the station. The lever 17' obviates this difficulty and positively prevents the release of the carrier and its propulsion from the station until the outer end of the lever has 45 been raised by the engagement of the part 17" therewith, said part 17" forming the upper portion of one member of the locking device carried by the basket, which is inserted into the other member of the carrier only 50 when the basket is raised for attachment to the carrier. It will be clear, therefore, that the lever 17' will remain in its locking position and the carrier cannot be discharged from the station until the basket is raised 55 and the lever tripped.

In various ways the details of construction herein may be modified without departing from the scope of my invention.

I claim as my invention:—

60 1. The combination, with a hanger and a line wire supported thereon, of a carrier, a rod projecting rearwardly from said hanger, a plunger having its forward end slidably supported on said line wire and its rear end 65 slidably supported on said rod, an operating

cord attached to the rear end of said plunger, the forward end of said plunger engaging said carrier to project it from the station.

2. The combination, with a clerk's station, 70 of a line wire and carrier, a latch yoke pivoted on said carrier, means at the clerk's station to engage and lock said latch yoke and a propelling plunger operating to engage and trip said latch yoke and project said 75 carrier from the station.

3. The combination, with a clerk's station, 80 of a line wire and carrier, an angular latch yoke pivoted on said carrier, a yieldingly mounted locking hook in the path of said latch yoke, means normally holding said hook in position to engage said latch yoke, said latch yoke having a depending arm and a reciprocating plunger operating to engage 85 said arm, release said latch yoke and propel said carrier from the station.

4. The combination, with a hanger, of barrels supported thereon and capable of rotary adjustment around said hanger, said barrels having a web between them, a line 90 wire mounted in said web, a carrier for said line wire, brackets having studs slideable in said barrels and means for securing them therein, pulleys mounted on said brackets, cords passing over said pulleys, and a basket 95 elevating hook carried by said cords, the adjustment of said brackets in said barrels allowing said hook and basket to be centered beneath said carrier.

5. The combination, with a hanger, of 100 barrels mounted thereon, brackets having studs fitting within said barrels, pulleys carried by said brackets, a cord passing over said pulleys, a basket elevating and lowering hook attached to said cord, depending arms 105 pivotally supported intermediate to their ends, a roller buffer carried by said arms in the path of the basket, and means yieldingly resisting oscillation of said arms.

6. A store service carrier station comprising a hanger, barrels supported thereon and having a connecting web provided with a hub, means securing said hub to said hanger, a line wire secured to said web, the rotation of said hub about said hanger permitting 115 the radiation of the line wire in any direction from said hanger, a carrier, brackets mounted in said barrels, pulleys mounted on said brackets, cords passing over said pulleys, and a basket engaging hook carried by 120 said cords.

7. A store service carrier station comprising a hanger, barrels suspended thereon having a connecting web between them, pulleys supported by said barrels, a basket elevating 125 cord and hook therefor, a line wire mounted in said web, a carrier for said line wire, a rod mounted in said web and projecting rearwardly therefrom, a plunger supported at one end on said rod and at its other end 130

on said wire and operating to propel said carrier from the station.

8. A store service carrier station comprising a hanger, barrels supported thereon and having a web between them, a line wire attached to said web, depending arms pivoted on said web, spring pressed pins slidable in guides on said barrels and pivotally connected with said arms and yieldingly resisting oscillation thereof in one direction, a basket buffer carried by said arms, and a basket raising and lowering device supported by said barrels.

9. A store service carrier station comprising a hanger, barrels supported thereon and having a web between them, a line wire mounted in said web, a carrier for said line wire, a latch yoke pivoted on said carrier, a spring pressed stud slidable in said web between said barrels and having a locking latch adapted to engage and lock said yoke and carrier, and means for simultaneously disengaging said yoke from said hook and propelling said carrier from the station.

25 10. A store service carrier station comprising a hanger, parallel barrels suspended thereon, studs fitting within the forward ends of said barrels and slidable therein and means for locking said studs in said barrels, 30 pulleys carried by said studs, a cord passing over said pulleys, a basket engaging hook attached to said cord, a carrier, the adjustment of said studs in said barrels permitting the centering of said hook with respect to 35 said carrier, and a propelling means for said carrier.

11. The combination, with a clerk's station, of a line wire and carrier, a locking means for holding said carrier temporarily in said station, a propelling means for said carrier, a basket, and means normally preventing the tripping of said locking means, said preventing means being actuated to release said locking means by the ascent of 45 said basket into engagement with said carrier.

12. The combination, with a clerk's station, of a line wire and carrier, a latch yoke pivoted on said carrier, means at the clerk's station to engage and temporarily lock said latch yoke and carrier, a propelling means, and means temporarily preventing the tripping of said latch yoke until the basket is lifted into engagement with said carrier.

55 13. The combination, with a home station, of a line wire and carrier, a lever pivoted in said carrier, a basket, said basket and carrier having interlocking members, said lever being disposed in position to be actuated by 60 the relative movement of said members, means for temporarily locking said carrier at the station, said lever normally preventing the release of said locking means when the basket is detached from said carrier and 65 being actuated by the attachment of the

basket to the carrier to release said locking means, and a carrier propelling device.

14. The combination, with a hanger, of barrels supported thereon and having an integral connection web between them, a line wire centered between said barrels and fitting within a socket in said web, and a tapered pin mounted in said web and extending transversely of said wire and contacting therewith, for the purpose specified.

70 15. The combination, with a hanger, a line wire and carrier, of brackets arranged in the front and rear of said hanger and adjustable horizontally toward and from one another, pulleys mounted in said brackets, 80 cords passing over said pulleys, a basket elevating hook carried by said cords, the horizontal adjustment of said brackets and pulleys allowing said hook to be centered beneath said carrier.

85 16. The combination, with a hanger, a line wire and carrier, of parallel horizontal members supported by said hanger and projecting in front and in the rear of the same, brackets having bearings in said members 90 in front of and in the rear of said hanger, the brackets in front of said hanger being adjustable toward or from the brackets in the rear of said hanger, pulleys carried by said brackets, cords passing over said pulleys, a basket elevating hook attached to said cords, the adjustment of said brackets and pulleys allowing said hook to be centered beneath said carrier.

95 17. The combination, with a hanger, of parallel members having a connecting web between them, said web having a hub to receive said hanger and on which hanger said hub is rotatable to allow said members to be revolved around said hanger, a line wire secured to said web, a carrier for said wire, pulleys mounted on said members, a cord passing over said pulleys, and a basket hook attached to said cord.

100 18. The combination, with a station and a line wire and carrier, of a latch yoke pivoted on said carrier, a locking latch adapted to engage said yoke and carrier when they enter the station, and a propelling plunger operating to engage and trip said latch to release said yoke and project said carrier from the station.

110 19. The combination, with a hanger, a line wire and carrier, of depending pivoted arms, a pulley carried by said arms, pulleys supported by said hanger, a cord passing over said pulleys and having a basket engaging hook, said arms depending into the path of the basket and means resisting oscillation of said arms.

120 125 20. The combination, with a hanger, of a line wire and carrier, a basket having a bail and means for interlocking with said carrier, an elevating cord having a hook to engage said bail, pivoted arms depending 130

vertically in the path of said basket and operating as a buffer in the path of said basket entering a station.

21. The combination, with a hanger, of a line wire and carrier therefor, a basket for said carrier and pivoted means depending vertically into the path of the basket entering the station and operating as a buffer therefor.
22. The combination with a station, of a line wire and carrier, a latch member on

said carrier, means at the station to engage and lock said member and a propelling plunger operating to engage and trip said latch member and project said carrier from 15 the station.

In witness whereof, I have hereunto set my hand this 24 day of April 1911.

CHARLES J. MILLER.
